SOCKET AND PLUG SWITCH

Philip Fuchs, Detroit, Mich., assignor of twelve and one-half per cent to Howard H. McLain, Detroit, and twelve and one-half per cent to Jack H. Miller, Walled Lake, Mich.

Application September 23, 1938, Serial No. 231,446

1 Claim. (Cl. 173—343)

My invention relates to electrical connections and has among its objects and advantages the provision of an improved socket and plug switch.

An object of my invention is to provide a socket and plug combination in which the parts are so devised as to facilitate connection. Means are incorporated for yieldingly latching the two parts into connected relation so as to prevent accidental disconnection. In addition, the socket and plug embody a novel switch which may be opened or closed through mere rotation of one part relatively to the other part to the end that the circuit may be opened or closed with the two parts in connected relation. The socket is characterized by a bore for the reception of the plug prong provided with contacts for connection with an electric cord with the bore and the prong so designed as to facilitate insertion of the prong into the bore. I provide means for indicating the on and off position of the plug.

In the accompanying drawing:

Figure 1 is a longitudinal sectional view illustrating the socket and plug in connected relation;

Figure 2 is a similar view with the socket and plug rotated 90° about their longitudinal axes;

Figure 3 is an end view of the plug;

Figure 4 is an end view of one part of the socket;

Figure 5 is a sectional view along the line 5—5 of Figure 1;

Figure 6 is an end view of the fore-end of the socket;

Figure 7 is a perspective view of the socket contact strip; and

Figure 8 is a perspective view of one of the contact strips associated with the plug.

In the embodiment selected to illustrate my invention, I make use of a socket 10 provided with a screw contact sleeve 12 adapted for connection with conventional lock sockets. Socket 10 is provided with slots 14 and 16 for the reception of contact strips 18 and 20, respectively. Contact strip 20 is provided with a hook 22 which hooks over the end of the wall 24, which wall is recessed at 26 and 28 for accommodating the hook. I recess the outer face of the socket 10 at 30 for partly housing the sleeve 12 and one end of the sleeve abuts the shoulder 32.

Contact strip 20 is bowed at 34 to extend through a slot 36 in the wall 34 to have electrical connection with the contact strip 38 carried by the prong 40 associated with the plug 42. Sleeve 12 includes a plurality of ears 44 which are bent over the end of the socket 10 with one of the

ears arranged in electrical conducting relation with the contact 20, see Fig. 1. Socket 10 includes a bore 46 for slidably receiving the prong 40. Contact strip 18 includes a reach 48 extending across the face 50 of the socket 10 and provided with an opening for the reception of a screw 52 molded in the end wall 54 of the socket. A cap 56 is bored at 58 for the reception of a nut 60 having threaded relation with the screw 52. One end 10 of the nut 60 presses the reach 48 against the face 50 for securing the contact 18, while the nut includes a flange 62 which presses the cap 56 against the end of the socket 10 for securing the two parts in connected relation. Flange 62 constitutes an electrical contact.

Contact 18 is bowed at 64 to extend through a slot 66 in the wall 68 for bringing the contact into conducting relation with the contact strip 10 anchored to the prong 40.

Screw 52 includes a head 72 positioned inside a split cup 74 arranged to have frictional connection with the head 76 of a shank 78 molded in the prong 40. The screw 52 extends through an opening in the split cup 74 and the head 72 of the screw holds the cup against the wall 54 for anchoring purposes. Head 76 is aligned with the split cup 74 and enters therein as the plug 40 is pushed home in the bore 46. The frictional relation between the split cup and the head is such as to effectively hold the plug 42 in connected relation with the socket 10 to prevent accidental disconnection of the two parts.

Contact strips 38 and 70 are molded into the prong 40 and include keys 80 molded into the material of the prong. Each contact strip 38 and 70 includes a right-angular bend 82 provided with an opening 84 for the reception of a screw 86 threaded into a sleeve 88 molded into the rib 90 of the cap 92 of the plug. These contact strips are identical in construction and are made secure in the same manner. Tightening of the screws 86 press the right-angular bends 82 firmly against the faces 94 of the ribs 90 for connecting the prong 40 with the cap 92. Screws 86 also constitute connecting means for the electric wires of the conventional plug which is threaded through the opening 96 in the cap 92.

Referring to Figure 5, the contact strips 38 and 70 lie within the cross sectional contour of the plug 40 and have depressions 100 for the reception of ribs 98 formed in the bows 34 and 64 of the contact strips 18 and 20. Contacts 38 and 70 are positioned at diametrically opposite points on the prong 40, while the prong is provided with diametrically opposite recesses 102 for the

reception of the ribs 100 on the contacts 18 and 20 when the plug 42 is rotated 90° relatively to the socket 10. Contacts 18 and 20 are associated as to have pressure relation with the prong 40. Thus the ribs 100 will snap into the depressions 98 in one position of the cap 92. In another position of the cap 92, the ribs 100 will snap into the recesses 102. With the prong 40 rotated sufficiently far to bring the recesses 102 into registration with the ribs 100 the circuit will be broken.

Rotation of the cap 92 sufficiently far to bring the strips 18 and 20 into contacting relation with the strips 38 and 70 will close the circuit. The circuit may be broken by pulling the plug 42 out of connected relation with the socket 10 in lieu of breaking the circuit through rotation of the plug. Figure 1 illustrates the socket 10 as including a small projection 104 and the cap 92 provided with a similar projection 106. Rotation of the plug 42 for bringing the projection 106 into registration with the projection 104 indicates a closed circuit. When the plug 42 is rotated sufficiently far to bring the ribs 98 into registration with the recesses 102, resistance against further rotation will indicate a broken circuit. The position of the prong 106 at this time provides a visual indicator for determining a broken circuit.

Prong 40 fits snugly inside the bore 46 but may be withdrawn easily after the head 76 has been pulled out of connected relation with the split cup 74. The split cup 74 has such holding relation with the head 76 as to prevent the assembly of Figure 1 to be positioned vertically with no danger of the socket 10 separating from the plug 42 under normal loads. Socket 10 as well as the plug 42 is formed of insulating material.

In the face 108 of the socket 10 I provide a

5 circular groove 110 for the reception of a ring 112 which has illuminating properties to provide location means in the dark. Face 108 includes a gentle curvature 114 for directing the head 76 into the bore 46. My invention embodies a socket and plug combination characterized by a single prong which may easily be inserted in the one bore 46. In the dark, positioning of the head 76 inside the illuminated circle 112 facilitates insertion of the prong 40.

10 Without further elaboration, the foregoing will so fully illustrate my invention that others may, by applying current knowledge, readily adapt the same for use under various conditions of service.

15 I claim:

20 In a socket and plug switch, a socket part having a bore and contacts for connection with a source of current and extending into said bore, a plug part having a prong provided with contact strips each having a terminal for connection with a wire of an electric cord, said contact strips being arranged to engage said first-named contacts when said prong is pushed home in said bore, said prong fitting snugly in said bore but being rotatable therein for bringing the contact strips into and out of engagement with said first-named contacts, said prong being movable longitudinally of the bore to permit connection and disconnection of said socket part and the plug part, said contact strips lying within the cross-sectional contour of the prong to permit a snug fit between the wall of said bore and the prong, said bore at its prong entrance end being flared to facilitate insertion of the prong, and an illumination means arranged concentrically about the flared end of said bore.
